UNITED STATES PATENT OFFICE

159,749

HAND LUGGAGE CASE

Osgar J. Ohanian, Philadelphia, Pa., assignor of one-half to Andrew Ohanian, Drexel Hill, Pa.

Application March 22, 1950, Serial No. 8,679

Term of patent 14 years

(Cl. D87—5)

To all whom it may concern:

Be it known that I, Osgar J. Ohanian, a citizen of the United States, residing at Philadelphia, State of Pennsylvania, have invented a new, original, and ornamental Design for a Hand Luggage Case, of which the following is a specification, reference being had to the accompanying drawings, forming part hereof.

Fig. 1 is a top plan view of a hand luggage case embodying my new design.

Fig. 2 is an end elevation of the same.

Fig. 3 is a side elevational view of the same.

Fig. 4 is a bottom plan view of the same.

I claim:

The ornamental design for a hand luggage case, as shown.

OSGAR J. OHANIAN.
